UNITED STATES PATENT OFFICE.

GEORGE C. WRIGHT, OF NEW YORK, N. Y., ASSIGNOR TO E. S. HIGGINS & CO.,
OF SAME PLACE.

DESIGN FOR A CARPET-PATTERN.

Specification forming part of Design No. 5,959, dated June 25, 1872.

Specification describing a Design for Carpets, invented by GEORGE C. WRIGHT, of New York, county of New York and State of New York.

The nature of my design is fully represented in the accompanying photographic illustration, to which reference is made.

A represents a panel ornamented on its outer edge with suitable band-work of Grecian order. H i G d g g is a group of flowers covering most of panel A. E is a center figure, upon which rests a garland or wreath of flowers, J. b and c are scrolls and band surrounding E, but so connected with c as to form ground-work C and D, both different kinds of mottled ground. a is a circular band surrounding set figure F. f are scrolls radiating from figure F and overlying H i G d. I h are figures of a shell-form, completing the frame-work surrounding panel and centers. I prefer to make the panel A white; panel E, maroon, shaded with black; F, green; G, the band, scarlet; B, white; J, or wreath, greens, pinks, purples, &c.; g g, in similar colors to J; C, a mottled ground, composed of light and dark drab, white, and ma-

roon; D, the same, substituting orange for dark drab; b, scarlet; a, green; f e d I h c, in "light two and three" yellow brown; H i in light two and three oak.

I do not consider the colors selected to be an essential element in my design.

I am aware that carpet-patterns composed of panels, scrolls, and flowers are not new, and lay no claim to those features.

The distinctive character of my design is found in the construction of bands surrounding panels and flowers, in combination with scroll-work and figures inwrought into bands, and resting on two styles of mottled ground.

What I claim as my invention is—

A design for carpets in which the panels, bands, flowers, and mottled ground are combined, substantially in the manner above described.

GEO. C. WRIGHT.
